ELLIPSE OR CIRCLE COMPASS

Joseph Weckert, Cloquet, Minn.

Application March 4, 1936, Serial No. 67,122

12 Claims. (Cl. 33—30)

My invention relates generally to an instrument for drawing and scribing circular, oval, and elliptical figures or curves, and an important object of the invention is to provide an instrument of this character which is readily accurately adjustable and which is capable of producing substantially perfect lines and figures.

Another important object of the invention is to provide a mechanically superior device of the character indicated which can at low cost be constructed in a long wearing and rugged form.

Another important object of my invention is to provide an instrument of the character indicated above which will remain in an adjusted position until re-adjusted.

Other important objects of my invention will be apparent from a reading of the following description in connection with the drawings, wherein for purposes of illustration I have shown a preferred embodiment of my invention.

In the drawings:—

Figure 1 is a general side elevational view of the embodiment showing the same in an operative position.

Figure 2 is a transverse vertical sectional view taken through the upper part of Figure 1.

Figure 3 is a horizontal sectional view taken through the cord reel.

Figure 4 is a transverse vertical sectional view taken through the joint structure of one of the connecting links.

Figure 5 is a horizontal sectional view taken through Figure 1 approximately on the line 5—5.

Figure 6 is a horizontal sectional view taken through Figure 1 approximately on the line 6—6 and looking downwardly.

Figure 7 is a transverse vertical sectional view taken through the main arm of the embodiment.

Figure 8 is a top plan view showing diagrammatically an adjusted operative position of the device showing the same completing a wide ellipse, and showing the positions which the relatively stationary legs would occupy in scribing a relatively narrow ellipse.

Figure 9 is a horizontal sectional view taken through Figure 7 approximately on the line 9—9.

Figure 10 is a horizontal sectional view taken through Figure 7 approximately on the line 10—10.

Figure 11 is an elevational view of a portion of the main arm looking at the reverse side thereof from that shown in Figure 1.

Referring in detail the drawings, the numeral 5 generally designates the adjusting screw which

has a smooth and pointed lower end 6 which passes through a sleeve 7 and said sleeve has diametrically opposed pairs of ears 9 which contain pivots 10 and 11 which pivot the lower ends of the connecting links 12 and 13 to the 5 said sleeve and which have their upper ends pivoted as indicated by the numerals 14 and 15 between the pairs of ears 16 and 17 extending inwardly from the upper part of the relatively stationary legs 18 and 19.

The stationary leg 18 is tubular in form and has extending from its lower end a surface engaging point 18a. At the outer side of the leg 18 and slightly elevated above the pair of ears 16 is the pair of ears 20 between which is pivoted 10 as indicated by the numeral 21 the cord reel 22 on which the cord 23 is wound, the cord passing downwardly and into the interior of the leg through an opening 24 and emerging again through an opening 25, near the point 18a. 15 Above the ears 20 the upper arms portion 26 inclines inwardly and is provided with ears 27 and 28 which are traversed by screws 29 and 30, the inner ends of which are socketed in diametrically opposite sides of a sleeve 31 which has a 20 smooth bore 32 turning on the screw 5, and a rest flange 33 on its upper end to be engaged by the lower end of a portion of the main 25 swingable arm to be described.

The screws 29 and 30 also traverse ears 34 30 and 35 on the inwardly inclined upper part 26' of the leg 19, and a locking nut 36 is threaded on the outer part of the screw 29 to clamp the respective ears on the upper ends of the legs 18 and 19 together and against the outside of the 35 sleeve 31, so as to lock these legs in adjusted positions relative to each other and relative to the screw 5.

Turning on the screw 5 above the sleeve 31 is the cylindrical portion 37 of the main swingable arm which is provided with a smooth bore 38 engaging the screw 5 and with a horizontal lateral arm 39 containing a pair of ears 40, and a lateral upwardly and outwardly inclining arm 41 which is provided with a pair of ears 42. Both 45 the ears 42 and the ears 40 are provided with respective pivot accommodating openings 43 and 44 which receive the pivots 45 and 46, respectively. A thumbscrew 90 traversing the cylindrical portion 37 can be adjusted to lock the cylindrical portion 37 in place.

The upper part of the cylindrical portion 37 is provided with a socket 47 whose mouth is provided with a radially inwardly extending retaining flange 48 which rotatably confines a 55

laterally enlarged head 49 on the lower end of the adjusting nut 50 which bears its lower end against the top of the flange 48 as clearly shown in Figure 2.

5 The nut 50 is threaded on the screw 5 and above it is threaded on the screw 5 a lock nut 51 which is designed to jam against the top of the nut 50 and lock the adjustment of the nut 50, whereby the position of elevation of the 10 cylindrical part 37 of the main swingable arm is determined on the screw 5.

The main swingable arm which is generally designated 52 comprises a straight tubular portion 53 which is open at its lower end and merges 15 at its upper end into the flattened triangular part 54 which has a reduced vertical extension 55 which itself has an upwardly and outwardly inclining arm 56 which has a flange 57 at its upper end through which is threaded the tension 20 adjusting screw 58 which has thereon a lock nut 59 for engaging the top of the flange 57 to lock the screw in place after adjustment. The screw has attached to its lower end as indicated by the numeral 60 the upper end of a contracting 25 spring 61 which has its lower end fixed to a lug 62 on the lower end of the cylindrical part 37. The greatest length of the portions 54 and 55 is on a line which leans away from the axis of the tube 52 in one direction, while the arm 30 56 leans more acutely in the opposite direction, but in the same plane in which the parts 54 and 55 lie.

The pivot 45 on the arm 39 engages the hole 63 on the part 54, which part is located between 35 the ears 40, of the arm 39, while another pivot 64 engages the hole 65 in the upper end of the part 55, and the pivot 64 engages the approximate middle of a beam 66 which has in its left hand end an elongated double curved slot 66' 40 in which the thumbscrew equipped pivot 46 works. The pivot 46 is mounted on the upper part of the arm 42 on the cylindrical part 37. The double curved slot 66' includes from right to left an upwardly and laterally curving part 45 merging into a laterally outwardly and downwardly curving part. When the desired adjustment of the pivot 46 along this slot is obtained the thumbscrew may be tightened to hold the adjustment. The beam 66 has in the opposite 50 or right hand and offset end a pivot 67 traversing the bar 68 in which is adjustably threaded the connecting rod 69 which has its lower end threaded and fastened with a lock nut indicated at 70 to a slide 72 which is slidably mounted 55 on the main arm 52.

Reference to Figure 5 shows the construction of the slide 72 which has the screw 73 traversing a slot arranged longitudinally through the side of the tube 52 and threaded as indicated 60 by the numeral 74 into the side of an inner tube 76 which has a part extending below the lower end of the tube 53 as clearly shown in Figures 1 and 7. This arrangement makes the tube 76 65 slidable relative to the tube 53 responsive to the movement of the slide 72 as it is worked by the connecting rod 69 which is, in turn, operated by the beam 66.

The lower part of the tube 76 has inserted therein a suitable scriber 77 which may be in 70 the form of a plain point or in the form of a pen or pencil.

Ball bearings 78 are seated in recesses in the sides of the upper part of the tube 76 while other ball bearings 79 are seated in recesses in the 75 sides of the lower part of the tube 53, so that

the tube 76 is both rotatably and slidably supported in spaced concentric relation to and within the tube 53, as clearly indicated in Figures 9 and 10.

To one side of the lower part of the tube 76 5 is mounted a V-shape bracket 80 one arm of which carries a rectangular member 81 which has at its radially inward end a three-quarter circular hook or eye 82 whose free end 83 terminates in close spaced relation to an angulated portion 84 of the member 81, this arrangement being for ready reception of the cord 20 and capable of retaining the same while the cord moves through the eye during the operation of the 10 swingable arm 52.

The reel 22 has its manually operated drum 21 mounted in the ears 20 on the leg 18 in such a way that sufficient retaining friction is exerted on the drum to retain the same in a selected rotated position to resist unwinding of 20 the cord 23 except when the drum is manually operated. The cord 23 emerging into two strands 85 and 86 from the opening 25 in the lower end of the leg 18, has the strand 85 passed through an eye 87 on the side of the lower part of the 25 leg 19 and the strand 86 is free of the eye 87, these strands becoming one in passing through and in the eye 82 as shown in Figure 1.

A thumbscrew 88 is provided for tightening the pen or pencil 77 used in the lower end of the 30 tube 76.

When it is desired to use the device to draw an elliptical figure, the nut 36 is loosened and the legs 18 and 19 adjusted the proper distance apart and then the nut 36 tightened. At this time 35 screw shaft 5 is adjusted so as to raise its pointed end above the pointed ends of the legs 18 and 19. The nut 36 is turned to adjust the member 37 so that the pencil point 77 is about one-eighth of an inch higher than the points of legs 18 40 and 19. The nut 46 must be loose to permit the arm 52 to swing outwardly under the action of the spring 61 though, of course, this outward swinging movement is limited by the cord which passes around the three parts 18, 19 and 76. 45 The arm 52 should be brought close to the leg 18 in starting the operation and then by moving the arm 52, using the member 81 as a handle, the figures can be drawn. By adjusting the legs 18 and 19 and the amount of cord passing 50 around the three parts 18, 19 and 76 ovals of different sizes and shapes can be drawn as well as curves.

When it is desired to use the device to draw a circle the screw shaft 5 is adjusted through 55 sleeves 7 and 31 and member 37 until its point is below the points of the legs 18 and 19 and the member 37 raised or lowered by turning nut 50 until the pencil point 77 is about even with the point of the screw shaft 5. If the cord is 60 allowed to remain in the eye 82 of the member 76 while the parts are being adjusted the adjustments are more easily made. Then the cord is removed from the eye 82 and the arm 52 is 65 permitted to be swung out by the spring 61 to the desired position. Then the nut 46 is tightened as is the screw. Then the parts are all held in adjusted position and the circle can be drawn by simply rotating the device on the pointed end of the screw shaft 5, the pencil 77 70 making the circle. The legs 18 and 19 can be used as a divider and if desired by lowering screw shaft 5 until its point is below the points of legs 18 and 19 this member 5 and the pencil 77 can be used as a divider, the arm 52 being 75

held in adjusted position by tightening the nut 46.

In drawing ovals and curves it is advisable to hold the device in a vertical position by grasping 5 the upper end of the screw shaft 5 and then grasp the handle 81 and turn the arm 52 which, of course, imparts rotary movement to the tubular part 37 which rotates around the shaft 5. In starting out the arm 52 should be near the 10 leg 18.

It will be seen that as the arm 52 is moved outwardly or inwardly the slot 66' and the bolt 46 passing through it will cause the pencil carrying part 76 to move outwardly and inwardly and 15 thus cause the pencil to remain on the surface being drawn upon.

What is claimed is:—

1. An instrument of the character described comprising a main swingable leg having a scribing point, and a relatively stationary support on which said main leg is swingably mounted, said support comprising a central rod designed to assume a perpendicular position relative to the work, a pair of relatively stationary legs each 25 having a point equipped lower end, first means pivotally connecting the upper ends of the stationary legs together and to said central rod, a vertically adjustable member on said central rod above said first means, and second means 30 rotatably mounting said main leg on said vertically adjustable member for rotation on the axis of said central rod.

2. An instrument of the character described comprising a main swingable leg having a scribing point, and a relatively stationary support on which said main leg is swingably mounted, said support comprising a central rod designed for perpendicular disposition relative to the work, a pair of relatively stationary legs each having a 40 point equipped lower end, first means pivotally connecting the upper ends of the stationary legs together and mounting the same on said central rod, a vertically adjustable member on said rod above said first means and on which said main 45 swingable leg is mounted, and spring tensioning means operating between said main leg and said vertically adjustable member, said main leg being arranged to swing on the axis of said central rod.

50 3. An instrument of the character described comprising a main swingable leg having a scribing point, and a relatively stationary support on which said main leg is swingably mounted, said support comprising a central rod arranged for perpendicular disposition relative to the work, a pair of relatively stationary legs each having a point equipped lower end, first means pivotally connecting the upper ends of the stationary legs together and mounting the same on said central 55 rod, a vertically adjustable member on said rod and carrying said main swingable leg for swinging on the axis of said rod, bracket means on said vertically adjustable member, said main leg including a rockable beam pivoted thereto, a pivotal and sliding connection between said bracket means and said beam, and a fixed pivotal connection between said bracket means and said main swingable leg.

4. An instrument of the character described 70 comprising a main swingable leg having a scribing point, and a relatively stationary support on which said main leg is swingably mounted, said support comprising a central rod arranged for perpendicular disposition relative to the work, a pair of relatively stationary legs each having a

point equipped lower end for engagement with the work, first means pivotally connecting the upper ends of the stationary legs together and mounting the same on said central rod, a rotatable vertically adjustable member on said rod, said member including bracket means, said main leg comprising a main portion and a beam pivoted thereto, a pivotal and sliding connection between said beam and said bracket means, a fixed pivotal connection between said main portion and said bracket means, said main portion of said main leg including a longitudinally slidable scribing member extending from the lower end thereof, and a connection rod operatively connected between said scribing member and said beam. 10 15

5. An instrument of the character described comprising a main swingable leg having a scribing point engageable with the work, and a relatively stationary support on which said main leg is swingably mounted, said support comprising a central threaded rod arranged for perpendicular disposition relative to the work, a pair of relatively stationary legs each having a point equipped lower end, first means pivotally connecting the upper ends of the stationary legs together and mounting the same on said central rod, a vertically adjustable member on said rod above said first means, said member comprising an unthreaded rotatable element on which said main leg is mounted and a threaded element operatively connected to said unthreaded elements being free to rotate relative to each other. 20 25 30

6. An instrument of the character described comprising a main swingable leg having a scribing point engageable with the work, and a relatively stationary support on which said main leg is swingably mounted, said support comprising a central rod arranged for perpendicular disposition relative to the work, a pair of relatively stationary legs each having a point equipped lower end, first means pivotally connecting the upper ends of the stationary legs together and mounting the same on said central rod, a vertically adjustable member rotatably mounted on said rod and carrying said main swingable leg, an extensible scribe on the lower end of said main leg, one of said stationary legs including a reel, rod wound on said reel and strung between said one leg to the remaining stationary leg and to said extensible scribe on the lower end of said main swingable leg. 35 40 45 50

7. An instrument of the class described comprising a central shaft, a sleeve on the shaft, a pair of legs having their upper ends pivoted to the sleeve whereby said legs can be moved toward and away from each other, means for locking the legs in adjusted position, a frame slidably arranged on the upper part of the shaft, a scribing leg pivoted to the frame, spring means for moving the last-mentioned leg outwardly, a reel carried by one of the first-mentioned legs, a cord on the reel, guide means for the cord on said one leg, a portion of the cord forming a loop for passing around the lower ends of the three 60 legs, a point carrying member slidably arranged in the scribing leg and means for sliding the member to keep the point on a surface on which the device rests as the scribing leg is swung outwardly or inwardly. 65 70

8. An instrument of the class described comprising a central shaft, a sleeve on the shaft, a pair of legs having their upper ends pivoted to the sleeve whereby said legs can be moved toward and away from each other, means for locking the 75

legs in adjusted position, a frame slidably arranged on the upper part of the shaft, a scribing leg pivoted to the frame, spring means for moving the last-mentioned leg outwardly, a reel carried by one of the first-mentioned legs, a cord on the reel, guide means for the cord on said one leg, a portion of the cord forming a loop for passing around the lower ends of the three legs, a point carrying member slidably arranged in the scribing leg and means for sliding the member to keep the point on a surface on which the device rests as the scribing leg is swung outwardly or inwardly, said means including a lever pivoted intermediate its ends to the frame and having a curved slot in one end thereof, a set screw passing through the slot into a part of the frame and means for connecting the other end of the lever to the sliding member.

9. An instrument of the class described comprising a threaded shaft having a pointed lower end, a sleeve having a smooth bore through which the shaft passes, a pair of arms having their upper ends pivoted to the sleeve, means for locking the arms in adjusted position, a frame including a tubular part having a smooth bore through which the upper end of the shaft passes, a nut rotatably connected with the tubular part and threaded on the shaft, a lock nut on the last-mentioned nut, a scribing leg pivotally connected with a part of the frame for swinging movement toward and away from the other legs, spring means for normally moving the scribing leg outwardly, a point carrying member slidably arranged in the scribing leg, a lever pivoted intermediate its ends to the frame and having a curved slot in one end portion, a set screw passing through the slot into a part of the frame for moving the lever on its pivot as the scribing arm moves inwardly and outwardly, the screw holding the lever against movement when the screw is tightened and a link connecting the other end of the lever with the sliding member in the scribing leg.

10. An instrument of the class described comprising a threaded shaft having a pointed lower end, a sleeve having a smooth bore through which the shaft passes, a pair of arms having their upper ends pivoted to the sleeve, means for locking the arms in adjusted position, a frame including a tubular part having a smooth bore through which the other end of the shaft passes, a nut rotatably connected with the tubular part and threaded on the shaft, a lock nut on the last-mentioned nut, a scribing leg pivotally connected with a part of the frame for swinging movement toward and away from the upper legs, spring means for normally moving the scribing leg outwardly, a point carrying member slidably arranged in the scribing leg, a lever pivoted intermediate its ends to the frame and having a curved slot in one end portion, a set screw passing through the slot into a part of the frame for moving the lever on its pivot as the scribing arm

moves inwardly and outwardly, the screw holding the lever against movement when the screw is tightened and a link connecting the other end of the lever with the sliding member in the scribing leg, a member having a bore through which the shaft passes and links pivotally connected to said member and also pivotally connected to the first-mentioned legs. 5

11. An instrument of the class described comprising a threaded shaft having a pointed lower end, a sleeve having a smooth bore through which the shaft passes, a pair of arms having their upper ends pivoted to the sleeve, means for locking the arms in adjusted position, a frame including a tubular part having a smooth bore through which the upper end of the shaft passes, a nut rotatably connected with the tubular part and threaded on the shaft, a lock nut on the last-mentioned nut, a scribing leg pivotally connected with a part of the frame for swinging movement toward and away from the other legs, spring means for normally moving the scribing leg outwardly, a point carrying member slidably arranged in the scribing leg, a lever pivoted intermediate its ends to the frame and having a curved slot in one end portion, a set screw passing through the slot into a part of the frame for moving the lever on its pivot as the scribing arm moves inwardly and outwardly, the screw holding the lever against movement when the screw is tightened and a link connecting the other end of the lever with the sliding member in the scribing leg, and means for fastening the tubular part of the frame to the shaft. 30

12. An instrument of the class described comprising a threaded shaft having a pointed lower end, a sleeve having a smooth bore through which the shaft passes, a pair of arms having their upper ends pivoted to the sleeve, means for locking the arms in adjusted position, a frame including a tubular part having a smooth bore through which the upper end of the shaft passes, a nut rotatably connected with the tubular part and threaded on the shaft, a lock nut on the last-mentioned nut, a scribing leg pivotally connected with a part of the frame for swinging movement toward and away from the other legs, spring means for normally moving the scribing leg outwardly, a point carrying member slidably arranged in the scribing leg, a lever pivoted intermediate its ends to the frame and having a curved slot in one end portion, a set screw passing through the slot into a part of the frame for moving the lever on its pivot as the scribing arm moves inwardly and outwardly, the screw holding the lever against movement when the screw is tightened and a link connecting the other end of the lever with the sliding member in the scribing leg, an adjustable flexible member forming a loop around the lower ends of the three legs. 50 55 60

JOSEPH WECKERT.
